VACUUM-TYPE CIRCUIT INTERRUPTER WITH
PRESSURE-MONITORING MEANSDonald W. Crouch, Newtown Square, Pa., assignor to
General Electric Company, a corporation of New
YorkFiled Mar. 17, 1966, Ser. No. 535,078
6 Claims. (Cl. 317—62)

This invention relates to means for monitoring the pressure inside a vacuum-type aircraft interrupter and, more particularly, relates to monitoring means capable of performing its intended pressure-monitoring function even while the interrupter is connected for service in a high voltage power circuit.

A typical vacuum-type circuit interrupter comprises a highly evacuated envelope and a pair of relatively movable contacts located within the envelope. When the interrupter is in closed position, the contacts are engaged and are thus capable of carrying current through the interrupter. Circuit interruption is effected by separating the contacts to draw an arc therebetween, soon after which the arc is extinguished and prevented from reigniting by the action of the vacuum.

To assure that the arc will be extinguished and prevented from reigniting in the desired manner, it is important that the pressure inside the envelope be maintained below a predetermined value.

An object of my invention is to provide monitoring means which is capable of monitoring this pressure while the interrupter is in service and which requires no vacuum seals or leads projecting into the envelope beyond those already present without the monitoring means.

Another object is to provide monitoring means of this type which will not impair the circuit-interrupting performance of the interrupter.

In carrying out the invention in one form, I provide a vacuum-type circuit interrupter that comprises an evacuated envelope, a pair of relatively removable contacts inside the envelope, and a tubular metal shield surrounding the contact and normally isolated from the contacts by evacuated space inside the envelope. The pressure inside the envelope is monitored by monitoring means comprising means for applying a high potential across the evacuated space between the shield and said contacts when the interrupter is closed. This potential is sufficiently low that no significant discharge is present across said space when the pressure inside the envelope is in a normal range but is sufficiently high to initiate a discharge across the space when the pressure inside said envelope is above the normal range. Current-responsive alarm or protective means is provided in circuit with said high potential-applying means for operating in response to the initiation of such a discharge across said space. Means responsive to initiation of an interrupter-opening operation is provided for removing said high potential from across said space when an interrupter-opening operation is initiated and for reapplying said high potential across said space when said interrupter is closed.

For a better understanding of the invention, reference may be had to the following description taken in conjunction with the accompanying drawing, wherein:

FIG. 1 is a schematic illustration of one embodiment of the invention showing the vacuum interrupter whose pressure is being monitored in the closed-circuit position.

FIG. 2 is a view similar to that of FIG. 1 except showing the interrupter in the open-circuit position.

Referring now to FIG. 1, there is shown a vacuum-type circuit interrupter that comprises a highly evacuated envelope 10 comprising a tubular casing 11 of suitable insulating material and a pair of metal end caps 12 and

2

13 closing off the ends of the casing. Suitable seals 14 are provided between the end caps and the casing to render the envelope vacuum-tight.

Located within the envelope 10 is a pair of separable disc-shaped contacts 17 and 18 shown in their engaged, or closed-circuit, position. The upper contact 17 is a stationary contact suitably secured to a conductive rod 17a, which at its upper end is united to the upper end cap 12. The lower contact 18 is a movable contact joined to a conductive operating rod 18a which is suitably mounted for vertical movement. The operating rod 18a projects through an opening in the lower end cap 13, and a flexible metallic bellows 20 provides a seal about the rod 18a to allow for vertical movement of the rod without impairing the vacuum inside the envelope 10. As shown in FIG. 1, the bellows 20 is secured by suitable seals at its respective opposite ends to the operating rod 18a and the end cap 13.

A basic function of the interrupter is to control the flow of an electric current through a high voltage power circuit in which it is connected. Such a circuit comprises a conductor 25 which is connected to the upper end of contact rod 17a, and a conductor 26 which is connected to the lower end of contact rod 18a. When the contacts are in their closed position shown, current can flow between the conductors 25 and 26 via the parts 17a, 17, 18, 18a of the interrupter.

Circuit interruption is effected by driving the lower contact rod 18a downwardly to separate the contacts 17 and 18. This establishes an arc between the contacts, which persists until the first natural current zero, assuming an alternating current circuit. The arc is prevented from reigniting after current zero by the high dielectric strength of the vacuum, thereby completing the interruption.

For condensing the metallic vapors that are liberated from the contacts by arcing, a tubular metal shield 30 is provided. Metal vapors projected by the arc from the gap between the contacts 17, 18 are intercepted and quickly condensed by this shield 30 during an interrupter operation. During an interrupter operation, as will soon be explained, this metal shield 30 is electrically isolated from both contacts 17 and 18. The shield 30 is suitably supported on an annular metal disc 32 that extends through the insulating casing 11 and is sealed to the insulating casing 11 by suitable vacuum-tight seals at its opposite sides.

For driving the movable contact 18 downwardly to initiate the above-described circuit interrupting operation, an insulating operating rod, or input member 35 is provided. This insulating operating rod 35 is biased in a downward direction by an opening spring 36, but it is normally restrained in its elevated position shown by means of a conventional trip latch 38. When the latch 38 is released, the opening spring 36 quickly expands and thus drives the rod 35 downwardly. A suitable stop 34 terminates this downward movement after a predetermined travel.

During the initial part of the opening operation, the rod 35 moves downwardly through a limited amount of lost motion travel without causing any downward motion of the movable contact 18. During this initial period the movable contact 18 is being held in engagement with the stationary contact 17 by means of a wipe spring 39. Upon completion of this lost motion travel, a shoulder 40 on insulating rod 35 strikes an annular abutment 42 carried by the contact rod 18a. When this occurs, the movable contact 18 is quickly driven out of engagement with the stationary contact 17, thereby establishing the above-described arc between the contacts, soon after which the arc is extinguished.

To assure that the arc will be extinguished in the desired manner, it is important that the static pressure inside

the envelope be maintained below a predetermined level. Typically, this level is about 10^{-3} millimeters of mercury. I have provided monitoring means 50 which is capable of continuously checking this pressure and of initiating appropriate protective steps should the pressure rise above the preselected level. In the illustrated embodiment, these protective steps comprise setting off an alarm and blocking a subsequent opening operation of the interrupter, as will soon be explained.

The monitoring means 50 comprises a suitable source 51 of high potential and a detector circuit comprising leads 52 and 54 connected across the source 51 for applying the high potential of the source between the shield 30 and one of the contact rods 17a. This high potential is, in effect, applied across the evacuated space 53 between the shield 30 and the conductive structure 12, 17a, 17, 18, 18a, 20, 13 that is electrically connected to the contact rod 17a. In one embodiment of the invention, the voltage applied by the high potential source is in the neighborhood of 10 to 15 kv. If a normal vacuum is present in the interrupter, i.e., a vacuum of about 10^{-4} millimeters of mercury or lower, no significant current flows across the evacuated space 53 between the leads 52 and 54. The high dielectric strength of the vacuum in the evacuated space 53 prevents any such current flow. But should pressure in the envelope rise to about 10^{-3} millimeters of mercury or slightly higher, a glow discharge will be initiated between the shield 30 and a portion of the conductive structure 12, 17a, 17, 18, 18a, 20, 13. Current immediately flows between the leads 52 and 54 through this discharge inside the envelope.

For sensing this current, I provide a detector 60 in the form of a sensitive current-responsive trip device that has a coil 62 connected in series with the leads 52, 54. When the coil 62 is energized by current exceeding a predetermined value, it operates an armature 63 to the left against a biasing spring 64, thereby releasing a latch 66 to effect tripping of an auxiliary switch 65. This auxiliary switch 65 includes three sets of contacts that are mechanically coupled together. The first set of contacts is a normally closed set 68 connected in series with coil 62 of the detector 60. The second set of contacts is a normally-open set 70 that is used for setting off an alarm when closed. The third set is a normally closed set of interlock contacts 72 that is connected in series with a coil 74 of the trip latch 38 for the interrupter.

When the latch 66 of the auxiliary switch 65 is released by the current-responsive detector 60, a spring 76 on the auxiliary switch operates the auxiliary switch 65, thereby opening contacts 68 and 72 and closing contacts 70. The closing of contacts 70 completes a circuit for an alarm A, thereby giving a warning that the pressure inside the envelope has risen to an undesirably high level.

The above-described opening of contacts 68 interrupts any current flowing through the detector circuit 52, 54, thereby terminating the electrical discharge inside the envelope 10. By quickly terminating the electrical discharge in this manner, I am able to prevent the interrupter from being damaged by the discharge. A continuing discharge not only could damage the interrupter but could set off a chain of events that could lead to damage to more expensive equipment associated with the interrupter. For limiting the current that flows through the discharge, a suitable current-limiting resistor 79 is connected in the detector circuit 52, 54.

Opening of the interlock contacts 72 serves to prevent the vacuum interrupter from being tripped open when the pressure inside the envelope 10 is at an undesirably high level. In this connection, opening of the contacts 72 effectively isolates the trip coil 74 from its source of tripping power. Opening of the interrupter is normally effected by closing an opening-control switch 80; but with the interlock contacts 72 open, closing of the switch 80 is no longer effective to initiate an interrupter-opening operation. Thus, when the pressure in the envelope 10 rises

to an undesirably high level, the interlock contacts 72 open to prevent tripping-open of the interrupter.

An important feature of my monitoring means is that its presence will not impair the circuit-interrupting ability of the vacuum interrupter. I prevent any such impairment of the interrupting ability by providing a switch 90 in series with the lead 54 of the detector circuit 52, 54. As shown in FIG. 1, this switch 90 is closed when the interrupter is closed. But just prior to separation of the contacts 18, 17 during an interrupter-opening operation the switch 90 is opened, thereby removing the high potential of the source 51 from the space 53 between shield 30 and the contact structure. FIG. 2 shows the parts after such an opening operation of the interrupter. By removing this high potential, the shield 30 is free to assume a floating potential intermediate that of the two contacts during interruption. This floating relationship of the shield 30 with respect to the contacts contributes to the interrupting ability of the interrupter, and I am able to preserve this floating relationship despite the presence of monitoring means 50.

It is to be noted that switch 90 is opened during an interrupter-opening operation before the contacts 17, 18 actually separate. This early opening of switch 90 is advantageous because it allows the shield 30 to assume its floating relationship during the entire interrupting operation.

For achieving early opening of the switch 90, I utilize the above described lost motion of insulating operating rod 35. As above described, the insulating operating rod 35 moves downwardly a predetermined initial distance before its shoulder 40 engages abutment 42 to initiate separation of the contacts 17, 18. A cam 92 is connected to the insulating operating rod 34, and downward motion of the rod 35 moves this cam 92 sufficiently to cause switch 90 to open before the contacts 17 and 18 of the interrupter part.

It should be noted that my monitoring means 50 requires no vacuum seals or leads projecting into the evacuated envelope 10 beyond those already present without the monitoring means. In this respect, the vacuum interrupter itself is of a conventional design. In this conventional design, the contact rod 17a and the supporting disc 32 for the shield 30 are exposed to the exterior of the envelope whether or not the monitoring means is present. By connecting the leads 52, 54 of my monitoring means to these parts 17a and 32, I am able to obviate the need for additional seals or leads beyond those already present.

It should be further noted that my monitoring means 50 is available to monitor the pressure in the vacuum interrupter even while the interrupter is connected for service in the high voltage circuit 25, 26. This monitoring function can continue without interruption so long as the interrupter is closed. It is only when the interrupter is opened or when the pressure rises to an abnormally high value that monitoring is discontinued.

When it is desired to return the interrupter 10 from its open position of FIG. 2 to its closed position of FIG. 1, the operating rod 35 is driven upwardly by suitable closing means (not shown); and such movement reengages contact 18 with contact 17. Upward movement of the operating rod 35 also recloses the switch 90, thus reapplying the voltage of source 51 to the space 53 inside the interrupter to resume monitoring.

While I have shown and described a particular embodiment of my invention, it will be obvious to those skilled in the art that various changes and modifications may be made without departing from my invention in its broader aspects; and I, therefore, intend in the appended claims to cover all such changes and modifications as fall within the true spirit and scope of my invention.

What I claim as new and desire to secure by Letters 75 Patent of the United States is:

1. In combination,
  - (a) a vacuum-type circuit interrupter comprising an evacuated envelope, a pair of relatively movable contacts inside the envelope, and a tubular metal shield surrounding the contacts and electrically isolated from said contacts when the interrupter is closed by evacuated space inside said envelope, 5
  - (b) means for monitoring the pressure inside said evacuated envelope while the interrupter is carrying current therethrough, comprising:
    - (i) high potential-applying means for applying a high potential across said space between said shield and said contacts when the interrupter is closed, 10
    - (ii) said potential being sufficiently low that no significant discharge is present across said space when the pressure inside said envelope is in a normal range, 15
    - (iii) said potential being sufficiently high to initiate a discharge across said space when the pressure inside said envelope is above said normal range, 20
    - (iv) current-responsive means connected in circuit with said high potential-applying means and operable in response to a discharge being initiated across said space, 25
    - (v) and means responsive to initiation of an interrupter-opening operation for removing said high potential from across said space when the interrupter-opening operation is initiated and for reapplying said high potential across said space when said interrupter is closed. 30
2. The monitoring means of claim 1 in which said means for removing said high potential comprises:
  - (a) a switch connected in series with said high potential applying means, 35
  - (b) means for closing said switch when the interrupter is closed,
  - (c) and means for opening said switch in response to initiation of an interrupter-opening operation. 40
3. The apparatus of claim 1 in combination with:
  - (a) means for opening said contacts comprising an operation-initiating member movable through a predetermined travel before causing said contacts to separate, 45
  - (b) and means for removing said high potential in response to said predetermined travel before said contacts separate.
4. The interrupter of claim 1 in combination with interrupting means controlled by said current-responsive means for interrupting the flow of current through said discharge upon operation of said current-responsive means. 50

5. In combination,
  - (a) a vacuum-type circuit interrupter comprising an evacuated envelope, a pair of relatively movable contacts inside the envelope, and a metal part electrically isolated from said contacts when the interrupter is closed by evacuated space inside said envelope, 5
  - (b) means for monitoring the pressure inside said evacuated envelope while the interrupter is carrying current therethrough, comprising:
    - (i) high potential-applying means for applying a high potential across said space between said metal part and said contacts when the interrupter is closed, 10
    - (ii) said potential being sufficiently low that no significant discharge is present across said space when the pressure inside said envelope is in a normal range, 15
    - (iii) said potential being sufficiently high to initiate a discharge across said space when the pressure inside said envelope is above said normal range, 20
    - (iv) current-responsive means connected in circuit with said high potential-applying means and operable in response to a discharge being initiated across said space, 25
    - (v) and means responsive to initiation of an interrupter-opening operation for removing said high potential from across said space when the interrupter-opening operation is initiated and for reapplying said high potential across said space when said interrupter is closed. 30
6. The monitoring means of claim 5 in which said means for removing said high potential comprises:
  - (a) a switch connected in series with said high potential-applying means,
  - (b) means for closing said switch when the interrupter is closed,
  - (c) and means for opening said switch in response to initiation of an interrupter-opening operation. 40
